Atty.

United States Patent Office.

SAMUEL DE VEAU, OF SYRACUSE, NEW YORK.

Letters Patent No. 105,439, dated July 19, 1870.

IMPROVED WASHING-MACHINE.

The Schedule referred to in these Letters Patent and making part of the same.

To all whom it may concern:

Be it known that I, SAMUEL DE VEAU, of Syracuse, in the county of Onondaga and State of New York, have invented a new and useful Improvement in Washing-Machines; and I do hereby declare that the following is a full, clear, and exact description thereof, which will enable those skilled in the art to make and use the same, reference being had to the accompanying drawing forming a part of this specification, in which—

Figure 1 is a longitudinal vertical section, and Figure 2 is a vertical cross-section.

Similar letters of reference indicate like parts.

In the accompanying drawing—

A is a hollow wheel, which is supported on a boiler, B, and rotated by a crank, a.

The boiler B is seated upon the furnace O for keeping the water in the machine hot.

The wheel is so constructed that a portion, A', is removable, as a cover, for opening and closing the wheel.

The clothes are placed in the wheel with balls, G, of wood, or other material, and when the wheel is rotated, the balls tread upon the clothes, the water being kept at the proper temperature by the furnace.

The inside of the wheel is provided with butments or ribs, h h, which lift the clothes from the sides of the vessel as it is rotated, and cause the water to pass under them.

The periphery of the wheel is made double and divided up into reservoirs or chutes which take up water and discharge it onto the clothes constantly when the wheel is in motion.

These chutes take up water from the boiler through their mouths f f and discharge it into the wheel by the openings e e, and this water is discharged onto the clothes with a force proportional to the length of the column of water in the chute.

Openings, n n, are made in the sides of the wheel, so that the redundancy of the water discharged into the wheel by the chutes can return to the boiler.

The cover A is fastened to the wheel by tenons C O, fig. 1, and hooks e e, fig. 2, or by other suitable devices.

The boiler B has a cover, b, which is large enough to inclose that part of the wheel that projects above the boiler B.

The furnace is constructed with double walls, k k, so that the clothes of the operator shall not be burned by coming in contact with its sides, and is made all open at the top, underneath the boiler.

This stove is made of galvanized sheet-iron. It can be dispensed with and the boiler mounted on an ordinary stove, but by means of said furnace O the washing can be done out of doors, or in some attachment of the house where no stove is ordinarily kept.

R is the furnace-door, which is held in place by a lip and spring, s r, and p is the stove-pipe.

By this construction of the wheel A the clothes are constantly supplied with a stream of water from above while they are being rolled over the butments and being tread upon by the balls.

Having thus described my invention,

What I claim, and desire to secure by Letters Patent, is—

1. The wheel A, made with a double periphery or series of chutes, e f, e f, in connection with the boiler B, for the purpose herein specified.

2. The furnace O, boiler B b, and wheel A A', all constructed and operating as and for the purpose herein set forth.

The above specification of my invention signed by me this 25th day of April, 1870.

SAMUEL DE VEAU.
